STEREOPHONOGRAPHIC APPARATUS AND
METHOD

William L. Douden, New York, N. Y., assignor to
Radio Corporation of America, a corporation of
Delaware

Application December 31, 1934, Serial No. 759,854

9 Claims. (Cl. 179—100.3)

This invention relates to an apparatus for so recording and reproducing sound that the listener can tell the direction of origin of the sound, and involves both a new apparatus and a new method for accomplishing said result. Heretofore there have been attempts to stereophonographically reproduce sound by the use of two or more soundtracks or sound records operating corresponding sound reproducers, and in some instances the procedure has been successful but has never been commercially adopted due to the great expense involved in the multiple sound records and the multiple recording and reproducing equipment. The present invention involves such sound recording and reproduction with a single record, and I effect the shifting of the apparent point of sound reproduction by a shifting of the axis of recording in relation to the axis of the soundtrack.

One object of the invention is to provide a method and apparatus for stereophonographically recording sound.

Another object of the invention is to provide a method and apparatus for stereophonographically reproducing sound.

Another object of the invention is to provide a novel photographic sound reproducer.

Another object of the invention is to provide an improved sound recorder.

Another object of the invention is to provide a sound record which may be reproduced either stereophonographically on the apparatus for such purpose or on a standard sound reproducer.

Another object of the invention is to provide a stereophonographic sound record occupying the minimum practical space.

Other and incidental objects of the invention will be apparent to those skilled in the art from a reading of the following specification and an inspection of the accompanying drawings, in which:

Fig. 1 is a diagrammatic illustration of my sound recording apparatus.

Fig. 2 is a diagrammatic illustration partly in section of the sound reproducing apparatus.

Fig. 3 is an illustration of the soundtrack.

Fig. 4 is an illustration of a special form of galvanometer for use in my apparatus, and

Fig. 5 is an illustration of a second form of galvanometer.

Referring first to Fig. 1: 1 and 2 indicate microphones located at the outer limits of the sound recording stage. These microphones may be of any convenient type capable of giving high quality response, and are connected to the amplifiers 3 and 4 of conventional type which serve to amplify the electrical impulses received from the microphones. The amplifiers 3 and 4 are connected to the usual mixer and power amplifier indicated at 5, which may be of any usual commercial type, and the acoustically modulated electrical output from the amplifier 5 actuates the galvanometer 6 in the known manner used in variable width sound recording, and is described and claimed in Kellogg Patent 1,740,406.

Connected to the output from the amplifiers 3 and 4 are rectifying amplifiers 6 and 7 which provide a direct current output corresponding to the envelope of the audio frequency input to each of the microphones. These amplifiers may be constructed, for example, as shown and described in MacDowell Patent 1,855,197.

The output from the amplifiers 6 and 7 is fed to solenoids 8 and 9 which operate upon cores 10 and 11 connected to the mask 12. It will be apparent that if the currents through the solenoids 8 and 9 are equal, the mask 12 will remain stationary in midposition while variations in the currents through the solenoids 8 and 9 will shift the mask 12 laterally by a corresponding amount.

The optical system used is of any convenient commercial type such, for example, as that shown in the Kellogg patent above referred to, and consists of an exciter lamp 13 from which the light is condensed on the mask 12 by the condenser lens 14. An optical system 15 is provided together with a lens 16 for condensing the light upon the mirror of the galvanometer 6 which vibrates about a horizontal axis, and an additional optical system 17 is provided which, together with 15 and 16, images the aperture in the member 12 upon the slit member 18 as indicated at 19. An additional lens 20 is provided between the slit member 18 and the film 21 for imaging the slit 22 in the member 18 upon the film.

It will be apparent from the foregoing that sound impressed on the microphones 1 or 2, or both, is converted into electrical impulses which vibrate the mirror of the galvanometer 6 about a horizontal axis, thereby moving the triangular image 19 over the slit 22 and illuminating correspondingly varying lengths of the slit; and this varying illumination is imaged upon the film 21 by the lens 20 thereby producing a variable width sound record of the type having modulation about both sides of an axis.

If the sound input is entirely to the microphone 1, it will be apparent that the amplifier 7 will give a correspondingly different current

through the solenoid 9 than does the amplifier 6 through the solenoid 8, and the mask 12 will be moved in accordance as, for example, toward the solenoid 9. If the sound being recorded is located 5 mid-way between the microphones 1 and 2, the outputs of the amplifiers 6 and 7 will be in and the member 12 will accordingly remain in mid-position, and if the output is greater to either microphone than to the other, the member 12 10 will be shifted a proportionate amount. This, obviously, will shift the image 19 longitudinally of a slit 22 and will shift the axis of the sound record in relation to the soundtrack 21 on the film. The position of the sound record in relation to the soundtrack area will accordingly indicate the position of the speaker in relation to the microphones.

The soundtrack produced by Fig. 1 is shown in Fig. 3 where 21 indicates the film and 25 indicates the sound record. It will be apparent that in this case the source of sound moved from near one microphone toward the other and became slightly louder as it approached the second microphone as is indicated by the movement of the 25 sound record from one side of the soundtrack to the other and with slightly increased modulation.

In order to reproduce the sound so that it will appear to come from the direction or position of its original source, I use the apparatus shown 30 in Fig. 2. In this apparatus, an exciter lamp 30 and condenser lens 31, a slit member 32 and an objective lens 33, all as customary in commercial sound reproducers are used to produce a brilliantly illuminated image of the slit 32 upon the 35 film 21 in the form of a narrow line of light. Light passing through the film 21 is directed by the lens 34 to the reflector 35. This reflector is coated with a layer of silver 36, 37 of varying thickness, being sufficiently thick at 36 to give 40 complete reflection of the light and tapering to substantially no reflection and complete transmission at 37, and with 50% reflection and 50% transmission at its mid-point. Any equivalent type of reflector may, of course, be used provided 45 it has complete transmission at one edge and complete reflection at the other edge with a gradually varying reflection and transmission between. The mirror 35 reflects light to the lens 38 which collects it upon the photocell 39, while light 50 transmitted by the mirror 35 is collected by the lens 40 upon the photocell 41. The photocells 39 and 41 actuate amplifiers of any usual commercial type indicated at 42 and 43 which in turn operate the loudspeakers 44 and 45 located in 55 substantially the same relative positions on the stage as were occupied by the microphones 1 and 2.

It will be apparent that this apparatus will 60 reproduce an ordinary sound record having the variable density type or a sound record of the variable area type having the modulation equally about the middle axis of the soundtrack in the usual manner, the sound being equally reproduced by the loudspeakers 44 and 45. If, however, a soundtrack of the type shown in Fig. 3 65 is reproduced in the apparatus when the soundtrack is imaged primarily upon the portion 37 of the mirror, the light will be substantially transmitted thereby and will be focussed upon the photocell 41, thereby actuating only the loudspeaker 44 and causing the sound to come from the corresponding side of the stage. As the soundtrack reaches mid-position, half of the light will reach 70 the photocell 41 and the other half will reach 75 the photocell 39, thereby equally actuating the

loudspeakers 44 and 45, and causing the sound to appear to come from the middle of the stage; while when the soundtrack image is adjacent the point 36 of the mirror 35 substantially all the light will be reflected to the photocell 39 and cause the sound to appear to come from the other loudspeaker 45.

It will be apparent that with this arrangement I can use modulation through either recording amplifier amounting to the full capacity 10 of the soundtrack as when the axis of the sound record is shifted to coincide with one side of the soundtrack the modulation becomes of the single or saw-tooth type and may extend over the entire width of the soundtrack. The one loudspeaker reproducing all the sound from one half 15 of the soundtrack and the other loudspeaker which reproduces the sound from the edge of the track opposite to the axis of the record reproducing the "peaks" of the modulation and thereby giving good quality sound reproduction.

Instead of using the movable diaphragm 12 and the galvanometer 6 as shown in Fig. 1, I may use a galvanometer such, for example, as that shown in Egerton Patent 1,605,930 in which the 25 mirror is capable of movement about two perpendicular axes, but I prefer to use a galvanometer of the type shown in Fig. 4. In this galvanometer, 60 indicates a metallic frame mounted pivotally on a vertical axis on the pivots 61 and 62. This frame carries two independent coils 63 and 64 which are respectively connected to the amplifiers 6 and 7 of Fig. 1, and this entire assembly is mounted between the pole-pieces 65 and 66 between which there is an appropriate magnetic field. It will be apparent that any lack of balance in the current through the coils 63 and 64 will evidence itself as a corresponding movement of the frame 60 in one direction or the other. Mounted within the frame 60 on appropriate pivots 67 and 68 is a shaft 69 carrying a mirror 70. To this mirror is connected a driving rod 71 which serves to vibrate the mirror about a horizontal axis in response to audio frequency currents. The modulation is supplied to the driving rod 71 by a vibrating reed 73 of an appropriate driving motor such, for example, as that shown in Dimmick Patent 1,936,833. The driving rod 71 is reduced in thickness at 72, as indicated, to permit it to flex about the vertical axis 45 defined by the pivots 61 and 62. It will be apparent that in this construction the mirror 70 50 will be capable of rapid vibrations about the horizontal axis in response to audio frequencies while the frame 60, which would not readily oscillate 55 at such high frequencies, follows the movement of the source of sound.

In the form of galvanometer shown in Fig. 5, the unit 80 is a complete galvanometer of the type shown and described in Dimmick Patent 1,936,833, and is mounted to pivot about a vertical axis on the pivots 81 and 82. An appropriate arm 83 is connected to the pivot 82 for the purpose of moving the galvanometer about the vertical axis about which it is maintained in approximate position by the spring 83. Solenoids 84 and 85 actuate the tension members 86 and 87 which are connected to opposite ends of the member 83, and thereby serve to move the galvanometer about a vertical axis. The solenoids 84 and 85 are connected to the amplifiers 6 and 7, while galvanometer 80 is connected to the amplifier 5 in the same manner as the galvanometer 6.

It will be apparent that in conjunction with 75

my apparatus I may also use a ground-noise reduction system of the same general nature as shown in the MacDowell patent, above referred to, and connected to the mask 12 to shift it vertically in the manner shown, described, and claimed in Maurer application Serial No. 602,135, filed March 31, 1932 and Kellogg application Serial No. 621,787, filed July 11, 1932. In such case, of course, the ground-noise reduction apparatus 10 would be connected to the output of the amplifier 5 in the manner there described.

Likewise, I may use the ground-noise reduction system of either Robinson Patent 1,854,159, or Hewlett Patent 1,853,812, or Hanna Patent 15 1,888,724, in which case the ground-noise reduction amplifier will be connected to the galvanometer 6, the vibrating means for the reed 72 or the galvanometer 80, so as to shift the spot of light 19 vertically in relation to the slit 22.

Having now described my invention, I claim:

1. Sound reproducing apparatus comprising means for illuminating a photographic sound-track, a plurality of photocells and a mirror for directing light passing through said sound-track to said photocells, one edge of the surface of said mirror being substantially completely reflecting for directing said lights to one of said photocells and the other edge of said mirror surface being substantially completely transparent for transmitting said light to another of said photocells.

2. In the method of sound recording which comprises the imaging upon a film of an illuminated portion of a slit which is illuminated by the image of a triangular aperture, the steps of vibrating said triangular image transversely of said slit in accordance with the acoustic vibrations to be recorded, and shifting the image longitudinally of the slit in accordance with the position of the acoustic vibrations to be recorded.

3. In the method of sound recording which comprises the imaging upon a film of an illuminated portion of a slit which is illuminated by the image of a triangular aperture, the steps of vibrating said triangular image transversely of said slit in accordance with the acoustic vibrations to be recorded, shifting the image longitudinally of the slit in accordance with the position of the acoustic vibrations to be recorded, and shifting the mean position of said image transversely of the slit in accordance with the average amplitude of the vibrations to be recorded.

4. Sound reproducing apparatus comprising means for illuminating a sound track varying in transparency along its length, a plurality of photocells, a mirror for directing light passing through said sound track to said photocells, one edge of the surface of said mirror being substantially completely reflecting and the other edge of the surface of said mirror being substantially completely transparent, amplifiers connected to said photocells and loudspeakers connected to said amplifiers, whereby the amplitude of response from each of the speakers is determined by the position of the sound recorded laterally of the sound track.

5. Sound reproducing apparatus comprising means for illuminating a sound track varying in

transparency along its length, a plurality of photocells, a mirror for directing light passing through said sound track to said photocells, one edge of the surface of said mirror being substantially completely reflecting and the other edge of the surface of said mirror being substantially completely transparent, amplifiers connected to said photocells, loudspeakers connected to said amplifiers, a sound record having its axis shifted in proportion to the position of the sound recorded thereon between said illuminating means and said mirror whereby the response of each of the loudspeakers is determined by the position of the said sound track.

6. Sound reproducing apparatus comprising means for illuminating a sound track varying in transparency along its length, a plurality of photocells, means for directing light passing through said sound track simultaneously to said photocells in a ratio of illumination determined by the position of the illumination on said directing means, amplifiers connected to said photocells and loudspeakers connected to said amplifiers, whereby the amplitude of response from each of the speakers is determined by the position of the sound recorded laterally of the sound track.

7. Sound reproducing apparatus comprising means for illuminating a sound track varying in transparency along its length, a plurality of photocells, means for directing light passing through said sound track simultaneously to said photocells in a ratio of illumination determined by the position of the illumination on said directing means, amplifiers connected to said photocells, loudspeakers connected to said amplifiers, a sound record having its axis shifted in proportion to the position of the sound recorded thereon between said illuminating means and said directing means whereby the response of each of the loudspeakers is determined by the position of the said sound track.

8. Sound reproducing apparatus comprising means for illuminating a photographic sound-track, a plurality of photocells and a mirror for directing light passing through said sound-track to said photocells, one edge of the surface of said mirror being substantially completely reflecting for directing said light to one of said photocells and the other edge of said mirror surface being substantially completely transparent for directing said light to another of said photocells, the proportion of light reflected to that transmitted varying uniformly between the said two edges.

9. Apparatus of the class described including two photocells, means directing a beam of light toward said photocells and a mirror for directing light from said beam to said photocells, one edge of the surface of said mirror being substantially completely reflecting for directing said light to one of said photocells and the other edge of the surface of the mirror being substantially completely transparent for directing said light to another of said photocells, the ratio of reflection and transmission being graduated between said edges.

WILLIAM L. DOUDEN.
